UNITED STATES PATENT OFFICE.

JACOB BRENNER, OF NEW YORK, N. Y.

CALENDAR.

SPECIFICATION forming part of Letters Patent No. 284,270, dated September 4, 1883.

Application filed March 30, 1883. (No model.)

To all whom it may concern:

Be it known that I, JACOB BRENNER, a subject of the Emperor of Germany, residing in the city of New York, county of New York, and 5 State of New York, have invented certain new and useful Improvements in Calendars, fully described and represented in the following specification and the accompanying drawings, forming a part of the same.

10 This invention relates to what are known as "perpetual calendars"—that is to say, those calendars which are not limited in their use to any particular year—it being the object of the invention to provide a calendar of this description which shall be simple in construction, reliable in operation, present an attractive and ornamental appearance, and which can be produced at a very trifling expense.

15 To these ends the invention consists in certain details of construction and combinations of parts, to be hereinafter fully described and particularly pointed out.

In the accompanying drawings, Figure 1 is a plan view of a calendar embodying the invention, certain of the parts being broken away for the sake of clearness of illustration. Fig. 2 is a cross-section of the same, taken upon the line *x x*, and Fig. 3 is a plan view of the month card or disk.

20 Referring to said figures, it will be seen that the principal parts of the structure consist of a plain card or disk, 8, having arranged around its edge a row of figures or characters indicating the days of the month, and an annular card or disk, 9, having arranged around its edge in like manner the names of the months of the year, these two being inclosed in a suitable casing, 10, the face 12 of which is provided with sight-openings 13 14, through 25 which the figures and names indicating the days and months are successively exposed as the cards are rotated. The card or disk 8 is supported upon a small shaft or stud, 7, which passes through the center of the card, and has its inner end supported in a pivotal bearing in a block, 17, rigidly secured to the back of the casing, while its opposite end extends through the front of the casing and terminates in a knob or button, 15, by which the stud can 30 be conveniently rotated. The card 8 is secured to the stud 7, so as to rotate therewith, in any convenient manner, as by the laterally-

projecting pin 6, which passes through a loop, 5, attached to the rear side of the card. The annular card 9, which carries the names of the months, is supported in the casing beneath or back of the card 8, but is placed eccentrically thereto, so that at one point of its revolution its edge is caused to project beyond the edge of the card 8, thereby permitting the names 55 of the months to be exposed through the opening 14, as shown in Figs. 1 and 2. In order that both the day and month cards may be operated by the same instrumentality, and the latter be always shifted at the proper time 60 without the performance of an extra operation, it is provided with a backwardly-extending rim or flange, 4, in which are formed a series of openings, 3, corresponding to the names of the months upon the face of the card, the rear 65 edge of said rim being in turn connected to a second annular card, 16, the inner periphery of which rests in a recess formed between the back of the casing 10 and the rabbeted edge 70 of the circular block 17. The stud 7 is provided with an arm, 1, which at each revolution of the stud passes into one of the openings, 3, and comes into engagement with its forward wall, 2, thereby turning the card 9 one step and bringing the name of the next 75 month into view.

The operation of the apparatus is as follows: Assuming that the parts are in the position shown in Fig. 1, the stud 7 will be turned step by step, bringing the numbers of the days upon the card 8 successively into view through the opening 13, until the last day of the month is reached, at which time the arm 1 will be at or near the position indicated by the dotted lines in Fig. 3. As the stud is turned to advance 80 the card 8, so as to expose the number for the first day of the next month, the arm 1 will be advanced to the position shown in Fig. 1, and during such advancement it will engage with one of the walls 2 and advance the card 9, so 85 as to expose the name of the next month, as shown in said figure, and so the operation will be repeated, the card 9 being advanced one step for each revolution of the card 8. At the end of those months in which there are less 90 than thirty-one days the card 8 will of course be advanced two, three, or four steps, as the case may be, at once.

The casing 10 and the other principal parts

of the calendar will usually be composed of card or paste board; but any other suitable or desirable material may be employed.

5 The casing 10 may be provided with any suitable means for suspending the calendar upon the wall of a room, or with an easel-leg or other suitable means for supporting it in an upright or inclined position upon a desk or table.

10 The face 12 of the casing may be provided with suitable ornamentation to give the calendar an attractive appearance; or it may bear any desired advertising matter.

What I claim is—

15 1. The combination, with the casing 10, of the rotating disk 8 and the annular rotating

flanged disk 9, having openings, and mounted eccentrically thereto and operated by an arm, as 1, extending from the stud of the disk 8, substantially as described.

2. The combination, with the casing 10, of the disk 9, provided with the flange 4 and openings 3, the stud 7, provided with arm 1, and the disk 8, carried by said stud, substantially as described.

20 In testimony whereof I have hereunto set my hand in the presence of two subscribing witnesses.

25 JACOB BRENNER.
